UNITED STATES PATENT OFFICE.

HENRY T. POTTER, OF NORWICH, CONNECTICUT.

IMPROVEMENT IN TOP ROLLS FOR DRAWING-FRAMES, &c.

Specification forming part of Letters Patent No. 142,509, dated September 2, 1873; application filed May 15, 1873.

To all whom it may concern:

Be it known that I, HENRY T. POTTER, of Norwich, in the county of New London and State of Connecticut, have invented an Improvement on Drawing-Rolls in Machinery for Preparing, Spinning, or Working Cotton, Wool, and other Fibers or Yarns, of which the following is a specification:

This invention is applicable, generally, to the top roll or presser of drawing-rolls used in machinery for preparing, spinning, or working various fibers or yarns, including doubling, and in which the upper roll is covered with leather or other soft material to give it elasticity, while the under roll presents a hard surface, and is usually fluted to give a firmer hold of the filaments. Ordinarily, it is customary to glue or otherwise fixedly attach the leather or other soft covering on such top rolls, which are usually made of wood, while the lower rolls are of metal. In a top roll thus covered, the attached leather covering, getting loose at one or more points, but fast generally, or at intermediate places, is apt to buckle and become defective in its bite or hold on the filaments being worked, such buckling producing an uneven surface, and, consequently, uneven drawing, which necessitates changing the roll before the covering is worn out. My invention consists in a top drawing-roll having its leather or soft covering arranged loosely around it—that is, fitting said cover close on or around, but not cementing it to, the roll, whereby any looseness forming in such free soft band, ring, or cover will necessarily run ahead, as it were, of the acting or biting portion of its surface on the filaments or yarn as they pass between it and the lower roll; or, in other words, any bagging or looseness in such free covering will be distributed ahead over the roll, thereby preventing buckling of the cover, and insuring its smoothness at all times where it is in

contact with, or in proximity to, the lower or driving roll. This gives an even drawing of the fiber, does away with the delay and expense of frequently changing the top roll, and utilizes the full wear of the cover. A top drawing-roll constructed in accordance with my invention may be applied with great advantage to preparing-machines in worsted-drawing, roving, and to spinning-frames.

In the accompanying drawing, which forms a part of this specification, Figure 1 represents an edge or peripheral view of a divided top drawing-roll, constructed in accordance with my invention; Fig. 2, a sectional view in direction of the length of the roll's axis; and Fig. 3, an end view of the roll.

Similar letters of reference indicate corresponding parts.

A represent the body of the roll, which may either be of wood, metal, or any other suitable material, and be either plane on its peripheral surface or cross-fluted, as shown in Fig. 3, to induce a better hold of the leather or other soft covering B upon it, such cover or covering being arranged loosely, though closely, as hereinbefore described, on or around the peripheral surface of the roll, and forming a free soft band or ring thereon, for the purposes hereinbefore specified. Said loose cover is guided or kept from getting out of place by collars or flanges b b on the sides or ends of the roll.

What is here claimed, and desired to be secured by Letters Patent, is—

A top drawing-roll having its leather or other soft covering fitted loosely upon it, so as to form a free soft band or ring, substantially as and for the purposes herein set forth.

HENRY T. POTTER.
